UNITED STATES PATENT OFFICE.

WILHELM SCHLOEMILCH, OF BERLIN, GERMANY, ASSIGNOR TO
GESELLSCHAFT FÜR DRÄHTLOSE TELEGRAPHIE M. B. H., OF
BERLIN, GERMANY.

RECEIVER FOR WIRELESS TELEGRAPHY.

No. 828,664.

Specification of Letters Patent.

Patented Aug. 14, 1903.

Application filed June 27, 1903. Serial No. 268,007.

To all whom it may concern:

Be it known that I, WILHELM SCHLOEMILCH, a subject of the King of Prussia, German Emperor, residing at Berlin, Germany, have invented certain new and useful Improvements in Receivers for Wireless Telegraphy, of which the following is a full, clear, and exact description.

In receiving electric oscillations of varying intensity a drawback is felt in that the ordinary coherer filings in the case of too high an intensity no longer decohere and the Morse transcriber consequently gives illegible characters or a continuous line or stroke. This is particularly inconvenient as it is difficult to recognize whether this results from too strong or too weak intensity, or from defective adjustment of the apparatus. Apart from the above drawbacks the coherer is deleteriously affected in the case of too intense radiation, which in most cases leads to a permanent defect therein. An effective protection of the coherer against too strong radiation could hitherto only be attained by constant watching or by precautions which diminish the intensity of the oscillations absorbed or received.

Now this invention has for its object, on the one hand to allow of a clear recording of the telegram in the case of too strong a receiver intensity by the use of a second receiver apparatus which is provided with a less sensitive coherer and which takes over the functions of the normal working apparatus usually employed as soon as the receiver intensity exceeds a given amount, and on the other hand to automatically protect the sensitive coherer of the main apparatus against too strong electric influences or impulses by switching it off by the second detector system on receiving oscillations which exceed a given intensity. It is possible thus to work without employing a skilled staff or an exact adjustment of the apparatus, and on the other hand the coherer is protected in all cases against too high intensities. It is preferable to employ an electrolytic detector as the less sensitive coherer of the greatest possible constancy and certainty of working, from which there results in addition to the automatic recording of the telegram also the possibility of hearing it. Both receiver systems may be arranged in such a way that

they each set in operation a separate Morse recorder or one common to both.

A form of construction of this improved switching is shown diagrammatically as an example in the accompanying drawing.

a indicates the aerial conductor which is earthed or connected with a capacity, with which conductor a portion of the self-induction coil b of the normal receiver-circuit is connected in the ordinary way. The receiver-circuit, in addition to this self-induction coil, also contains a coherer c and a condenser d and may be opened by means of a contact-armature f. Parallel to the condenser d, a relay g lies in the ordinary way in series with a small source of current. As soon as the coherer responds to the action of the arriving electric waves, a circuit is formed over the coherer which causes the relay g to respond. Hereby the Morse apparatus h and the local circuit containing the source of current i is closed, and in this way the Morse recorder is set in operation.

The connections hereinbefore described are well known and may be variously modified to attain its object.

Now according to the invention a second receiver-circuit is connected with the aerial conductor, and in the present case consists of a condenser k, a variable self-induction coil l and an electrolytic detector m with which a relay n and a battery o are connected in parallel.

As the electrolytic detector in combination with a recording apparatus acts substantially less sensitively than the filings-coherer c, it is here provided in order to take over the action of the latter as soon as the receiver energy increases beyond a given amount which would be deleterious to the coherer c. For this object the relay n is so adjusted that it corresponds exactly to the point when this given amount in the supply of energy is attained. The local circuit containing the Morse apparatus h is then closed by the relay n over a side switch or shunt in which an electromagnet p governing the contact-armature f lies. By means of this closing of the circuit the Morse apparatus h and also the electromagnet p are excited and by the latter the circuit of the coherer opened, so that a further increase in the energy introduced can no longer damage the sensitive co-

herer and all further signals arriving are transmitted to the Morse apparatus merely by means of the electrolytic detector *m*. In order to retain the contact-armature *f* in its attracted position and so to permanently keep open the coherer-circuit after it has been once opened, a pawl *q* is provided which is connected with the armature of an electromagnet *r*. The latter is inserted in the transmitter-circuit which contains the source *s* of the transmitter energy (an alternating-current dynamo.) The consequence of this is, that the coherer-circuit remains broken until a transmitter-circuit, opened during the receiving, is again closed by means of the switch *t* for the purpose of transmitting a message. Of course the coherer-circuit may also be closed earlier by a temporary switching on of the transmitter-circuit. The armature of the electromagnet *r* is also connected with a contact *u* over which the aerial conductor *a* is connected with the earth. The object of this precaution is to prevent the detectors from being excited by electric currents proceeding from the earth during the transmission.

The possibility of being able to easily give the electrolytic detector *m* any desired degree of sensitiveness allows of the arrangement hereinbefore described being also employed as an apparatus for recording telegrams which are transmitted from its own station. It has in fact been found necessary in practice to have a check as to whether the transmission of the aerial conductor is in correct correspondence with the exciter-circuit, that is to say whether the energy corresponding to the sparks ascertainable in the spark-gap is also actually transmitted to the aerial conductor system. A sure check as regards this can only be carried out with difficulty, as the respective interruptions of working—that is to say, by the use of a Leyden jar—cannot always be easily recognized. Now as the electrolytic detector, in the present invention, must be substantially less sensitive than the coherer, it is easy to record by this detector the powerful wave impulses despatched from the adjacent transmitter. For this it is sufficient to arrange at some distance from the aerial conductor *a* a second short auxiliary wire which is connected with the receiver system instead of the disconnected aerial conductor *a*. The telegraphist is thus in a position to supervise, from the working of the Morse apparatus of the transmitting-station, the correct delivery of the signals, and to be able to immediately remove any impediments. At the same time the arrangement combines the advantages of a recording apparatus providing a check over the signals given by the telegraphists. It may also be further observed that instead of the filings-coherer *c* any other sensitive coherer may be

employed and also, instead of the electrolytic detector any less sensitive detector may be employed. In the present case the connections are so arranged that both detectors and receiver-circuit operate a common Morse apparatus. It is evident without further explanation that instead of this, each receiver-circuit and detector may act in conjunction with a separate Morse apparatus. Instead of making the movement of the pawl *q* dependent on the operation of the transmitter-circuit, it may be effected from another separate local circuit, or even be done by hand.

What I claim as my invention, and desire to secure by Letters Patent of the United States, is—

1. In a receiver for wireless telegraphy, a receiver-circuit which acts together with two detectors of different degrees of sensitiveness, and means operated by the less sensitive detector for protecting the more sensitive detector against too high intensities substantially as described.

2. In a receiver for wireless telegraphy, a receiver-circuit which contains two detectors of different degrees of sensitiveness, and means operated by the less sensitive detector for disconnecting the more sensitive detector from the receiver-circuit substantially as described.

3. In a receiver for wireless telegraphy, a receiver-circuit, two detector-circuits electrically connected with the receiver-circuit, the detector of one circuit being less sensitive than the detector of the other circuit and means operated by the less sensitive detector for disconnecting the more sensitive detector from the receiver-circuit, substantially as described.

4. In a receiver for wireless telegraphy, a receiver-circuit, two detector-circuits electrically connected with the receiver-circuit, the detector of the one circuit being less sensitive than the detector of the other circuit, a relay in each detector-circuit and a recording apparatus successively operated by both relays substantially as described.

5. In a receiver for wireless telegraphy, a receiver-circuit, two detector-circuits electrically connected with the receiver-circuit, the detector of the one circuit being less sensitive than the detector of the other circuit, a relay in each detector-circuit, a recording apparatus successively operated by both relays and means operated by the less sensitive detector for breaking or opening the circuit of the more sensitive detector substantially as described.

In witness whereof I hereunto subscribe my name this 9th day of June, A. D. 1905.

WILHELM SCHLOEMILCH.
